REMOTE CONTROL APPARATUS

Paul P. Stoker, Wilkinsburg, Pa., assignor to The Union Switch & Signal Company, Swissvale, Pa., a corporation of Pennsylvania

Application January 7, 1933, Serial No. 650,667

3 Claims. (Cl. 246—3)

My invention relates to remote control apparatus, and has for an object the provision of novel and improved apparatus for controlling railway traffic governing devices such as switches 5 and signals from a distant point.

More specifically, my invention relates to manually controlled apparatus, such for example as code responsive mechanism operated by coded current transmitted from a train dispatcher's 10 office, for locking or unlocking a track switch of the well known spring type. My invention also relates to means for permitting traffic movements in a given direction over the switch only if the switch is locked, and to means for permitting 15 traffic movements in an opposite direction over the switch only if the switch is unlocked.

The apparatus of my invention is an improvement over that disclosed in the copending application Serial No. 125,659, filed July 29, 1926, by 20 Herbert A. Wallace, for Railway traffic controlling apparatus.

I will describe one form of apparatus embodying my invention, and will then point out the novel features thereof in claims.

25 The accompanying drawings, Figs. 1a and 1b, when placed side by side with Fig. 1a on the left, constitute a diagrammatic view showing one form of apparatus embodying my invention.

Referring to the drawings, the reference character X designates a stretch of single track 30 railway which is connected with tracks Y and Z by means of a switch F.

Switch F may be biased to the normal position, in which it is shown, by some suitable means 35 which may, for example, be of the well known spring type. Switch F may be manually movable to its reverse position by suitable means not shown in the drawings, and may also be movable to its reverse position by a train going over the 40 switch in the trailing direction, that is, from track Z to stretch X.

Rails 1 and 1^a of stretch X and of track Y are divided by means of insulated joints 3 into sections A—B, B—C and C—D. A track circuit 45 is provided for each of these sections, and includes a track battery 4 connected across the rails adjacent one end of the section, and a track relay, designated by the reference character T with a distinguishing exponent, connected across 50 the rails adjacent the other end of the section.

Signals, each of which is designated by the reference character S with a distinguishing exponent, govern traffic movements in both directions over switch F. Signals S² and S³ govern 55 traffic movements in the trailing direction over

switch F from tracks Y and Z, respectively, to stretch X, and signal S¹ governs traffic movements in the opposite or facing direction over switch F from stretch X to track Y. As here shown, each of the signals S is of the color light type, although 5 it is to be understood that my invention is not limited to this particular type of signals. Signals S are shown having a red or stop lamp R and a green or proceed lamp G.

A lock bar d is rigidly secured to switch F for 10 engagement by a dog a, by means of which switch F may be locked in its normal position only. Dog a is actuated by a motor Q which may be of any suitable type but which, as here shown, is an electric motor having an armature 49 and 15 a field winding 52.

In conjunction with dog a, motor Q actuates a contact 51 which is closed in a reverse operating circuit for motor Q at all times except when dog a reaches its final position for unlocking bar 20 d, and which is closed in a normal operating circuit for motor Q at all times except when dog a reaches its final position in engagement with bar d. Dog a actuates a contact 33 which is closed 25 only when dog a is in position for locking bar d and also actuates a contact 37 which is closed only when dog a is out of engagement with bar d.

Operation of motor Q is controlled by its contact 51, and by a polarized switch relay W. Relay W, when energized in what I shall call the normal 30 direction, causes motor Q to move dog a into position for locking bar d. Relay W, when energized in the opposite or reverse direction, causes motor Q to move dog a out of engagement with bar d.

Switch F actuates a circuit controller, commonly known as a point detector, having a contact 20 which is closed only if the switch points are in their proper condition while switch F is in its normal position.

A hand crank N is provided adjacent switch 40 F for emergency use by a trainman to manually move dog a out of engagement with bar d, when such action becomes necessary. For this use, the trainman will place crank N in the position in which it is shown in dash lines in the drawings, thereby displacing a contact 19 to its open position r. He will then operate crank N to disengage dog a from bar d. Contact 19 is included in the pickup and stick circuits for two code-controlled stick relays U¹ and U³, and will therefore open 45 any of these circuits which may be closed. The energizing circuits for relay W include contacts of relays U¹ and U³, and hence relay W will also be deenergized as long as contact 19 is open. Relays U¹ and U³ also control signals S, and 50 55

therefore each of the signals will indicate "stop" as long as contact 19 is open.

Relay W is controlled by switch contact 20, by track relay T², and by stick locking relays each 5 of which is designated by the reference character M with a distinguishing exponent, as well as by relays U¹ and U³. Relays U¹ and U³ determine the direction of energization of relay W.

Relay M¹ becomes deenergized when signal S¹ 10 is controlled by a relay H¹ to indicate "proceed". If signal S¹ is again controlled by relay H¹ to indicate "stop" before a train passes signal S¹, a slow pick-up relay E will become energized and will cause relay M¹ to again become energized 15 upon the lapse of a measured period of time after such control of signal S¹ to indicate "stop". Relay M² is similarly controlled by relays H² and H³ in connection with signals S² and S³, respectively.

20 The clearing of each of the signals S is controlled by the associated relay H which has a reference character corresponding to that of the signal. Energization of each relay H is caused by energization of one or the other of the relays U¹, U² and U³. Such energization of relays H can occur only if dog a is in the position corresponding with the energization of relay W controlled by relays U¹ and U³.

25 Energization of relays U¹, U² and U³ is controlled by manually controlled receiving mechanism designated by the reference character L, which is indicated in Fig. 1a, as receiving various control codes, and which is selectively responsive to these codes. As also indicated in 30 Fig. 1a, transmitting apparatus designated by the reference character K and located at a remote point such, for example, as a train dispatcher's office, transmits current at various control codes over line wires 58 and 59 for controlling receiver L. Apparatus K is controlled by a lever V and by a push button contact P, both of which are manually operable by the train dispatcher.

35 Receiver L includes normally open contacts 11, 45 16 and 39 and normally closed contacts 12 and 40 which are selectively responsive to the control codes at which current is supplied by transmitter K to receiver L. Receiver L also includes indication control devices I¹, I² and J for controlling the transmission of indication codes to the indication receiving portion of transmitter K.

40 Lever V has a normal position n, a left reverse position f, and a right reverse position t. A contact 56 operated by lever V is closed only when lever V occupies its t position, and a contact 57 55 operated by lever V is closed only when lever V occupies its f position. Push button contact P may be of the type which is spring biased to the open position.

50 The closing of contact 56 by operation of lever V to its t position causes transmitter K to supply current to receiver L at such a code as to open contacts 12 and 40 for a brief period and then to close contact 11. The closing of contact 57 by operation of lever V to its f position causes transmitter K to supply receiver L with current of such a code as to open contacts 12 and 40 for a brief period of time and then to close contact 65 16. If push button contact P is closed while contact 57 of lever V is closed, transmitter K will supply receiver L with current at such a code as to close contact 39.

Having described in general the arrangement 75 and location of the various parts of the appa-

ratus embodying my invention, I will now describe in detail the operation of the apparatus.

As shown in the drawings, all parts are in their normal condition, that is, lever V is in its n position; each of the track sections shown in the drawings is unoccupied; switch F is in its normal position; each of the code contacts 11, 16 and 39 of code receiver L is open and contacts 12 and 40 are closed; each of the relays E, H, U, and W and indication devices I is deenergized; 10 indication device J and relays M are energized; the red or stop lamp R of each of the signals S is lighted by a circuit which is supplied with current from terminal b of a source not shown in the drawings, through the back point of a 15 contact 5 of the associated relay H, and the lamp R to terminal o of the same source of current; and dog a is in the position for locking bar d.

The circuit by which relay M¹ is energized is a stick circuit passing from terminal b, through 20 contact 6 of relay H¹, wire 44^a, front point of contact 7 of relay M¹, and the winding of relay M¹ to terminal o. The circuit by which relay M² is energized is a similar stick circuit passing from terminal b, through contact 6 of relay H², 25 contact 6 of relay H³, front point of contact 7 of relay M², and the winding of relay M² to terminal o. The circuit by which indication device J is energized passes from terminal b, through the back point of contact 53 of relay H³, back point of contact 54 of relay H², back point of contact 55 of relay H¹, and the winding of device J to terminal o.

I will assume that the dispatcher desires to 35 permit an eastbound train, that is, a train moving from left to right as shown in the drawings, to proceed over switch F in the normal position. He will therefore move lever V to its t position. Contact 56 of lever V will therefore become closed, causing transmitter K to supply current 40 to receiver L of the code which will cause contact 11 of receiver L to become closed. Relay U¹ will then be energized by its pickup circuit passing from terminal b, through contact 11, 45 winding of relay U¹, and contact 19 associated with crank N to terminal o. Relay U¹, upon becoming energized, will complete its own stick circuit passing from terminal b, through contact 12 of receiver L, contact 13 of relay T², contact 14 of relay U³, contact 15 of relay U¹, winding 50 of relay U¹, and contact 19 associated with crank N to terminal o.

55 Relay U¹, upon becoming energized, will also complete a normal energizing circuit for relay W, passing from terminal b, through contact 20 of switch F, contact 21 of relay T², wire 22^a, front point of contact 23 of relay U¹, contact 24 of relay M¹, contact 25 of relay M², winding of relay W, and the back point of contact 26 of relay U³ to terminal o. Since dog a is already in 60 the position for locking bar d and motor Q is in the corresponding position, the circuit for operating motor Q to this position will be open at its contact 51 although contacts 47, 48 and 50 of relay W in this circuit will be closed.

65 With relay U¹ energized and with dog a in the position for locking bar d, relay H¹ will become energized by its circuit passing from terminal b, through contact 20 of switch F, contact 21 of relay T², wire 22^b, contact 27 of relay E, wire 70 28^a, contact 29 of relay U¹, contact 30 of relay H², contact 31 of relay H³, contact 32 of relay T³, contact 33 of dog a, and the winding of relay H¹ to terminal o.

75 Relay H¹, upon becoming energized, will open,

at its contact 6, the stick circuit previously traced for relay M¹ which will therefore become deenergized and open, at its contact 24, the circuit previously traced for relay W. Relay H¹, upon 5 becoming energized, will open, at the back point of its contact 5, the circuit for lighting lamp R of signal S¹, and will then complete, at the front point of its contact 5, the circuit for lighting lamp G of signal S¹. Relay H¹, upon becoming energized, will also open, at the back point of its contact 55, the circuit previously traced for device J, and will then complete a circuit for energizing indication device I¹, passing from terminal b, through the back point of contact 53 10 of relay H³, back point of contact 54 of relay H², front point of contact 55 of relay H¹, and the winding of indication device I¹ to terminal o.

If now an eastbound train enters section A—B, relay T¹ will become deenergized. This will, 20 however, cause no change in the condition of any other part of the apparatus, since contacts 8 and 36 of relay T¹ are included in circuits which are already open at other points.

When the train enters section B—C, relay T² 25 will become deenergized, and will open, at its contact 21, the circuit previously traced for relay H¹ and also the normal energizing circuit traced for relay W. The circuit for relay W is, however, already open at contact 24 of relay M¹. Relay H¹, upon becoming deenergized, will open, at the front point of its contact 5, the circuit for green lamp G of signal S¹, and will then again complete, at the back point of its contact 5, the circuit for lamp R of signal S¹. Relay H¹ will also open, 30 at the front point of its contact 55, the circuit traced for indication device I¹, and will again complete, at the back point of its contact 55, the circuit for indication device J. Relay T², upon becoming deenergized, will also open, at its contact 13, the stick circuit previously traced for relay U¹, thereby restoring relay U¹ to its normally deenergized condition.

When the train enters section C—D, relay T³ 45 will become deenergized and will therefore complete a pickup circuit for relay M¹, passing from terminal b, through contact 6 of relay H¹, wire 44^b, contact 8 of relay T³, contact 9^a of relay T², and the winding of relay M¹ to terminal o. Relay M¹, upon becoming energized, will complete, 50 at the front point of its contact 7, the stick circuit previously traced for this relay.

I will now assume that, after all parts of the apparatus have been returned to their normal condition, the dispatcher desires to permit a 55 westbound train to move from track Z over switch F to stretch X. He will therefore move lever V to its f position, causing contact 57 of lever V to become closed. Contact 57, upon becoming closed, will cause transmitter K to supply receiver L with current of a code which will open contacts 12 and 49 of receiver L for a brief period and which will then close contact 16 of receiver L.

Contact 16, upon becoming closed, will complete a pickup circuit for relay U³, passing from terminal b, through contact 16, winding of relay U³, and contact 19 associated with crank N to terminal o. Relay U³, upon becoming energized, will complete its own stick circuit, passing from 65 terminal b, through contact 12 of receiver L, contact 13 of relay T², contact 17 of relay U¹, contact 18 of relay U³, winding of relay U³, and contact 19 of crank N to terminal o. Relay U³, upon becoming energized, will complete a reverse energizing circuit for relay W, passing from ter-

55 minal b, through the front point of contact 26 of relay U³, winding of relay W, contact 25 of relay M², contact 24 of relay M¹, and the back point of contact 23 of relay U¹ to terminal o.

Relay W, upon thus becoming energized by 5 current of reverse polarity, will complete a reverse operating circuit for motor Q, passing from terminal b, through contact 47 of relay W, contact 48 of relay W in the right-hand position, armature 49 of motor Q, contact 50 of relay W 10 in the right-hand position, contact 51 of motor Q, and field winding 52 of motor Q to terminal o. Motor Q will then move dog a out of engagement with bar d. Dog a will therefore open its contact 33, and will, at the end of its unlocking 15 stroke, close its contact 31. Motor Q, at the end of this operation, will open its contact 51 in the reverse operating circuit previously traced, but contact 51 will now be closed in the normal operating circuit for the motor. 20

With relay U³ energized, and with dog a out of engagement with bar d, a circuit will be completed for energizing relay H³, passing from terminal b, through contact 20 of switch F, contact 21 of relay T², wire 22^b, contact 27 of relay E, 25 wire 28^b, contact 34 of relay U³, contact 35 of relay H¹, contact 36 of relay T¹, contact 37 of dog a, contact 38 of relay U², and the winding of relay H³ to terminal o.

Relay H³, upon becoming energized, will open, 30 at its contact 6, the stick circuit previously traced for relay M², thereby causing relay M² to become deenergized. Relay M² then opens its contact 25, causing relay W to be deenergized. Relay H³, 35 upon becoming energized, will also open, at the back point of its contact 5, the circuit for red lamp R of signal S³, and will complete, at the front point of its contact 5, a circuit for lighting green lamp G of signal S³. Relay H³, upon becoming energized, also opens, at the back point 40 of its contact 53, the circuit traced for indication device J, and completes, at the front point of its contact 53, a circuit for energizing indication device I², passing from terminal b, through the front point of contact 53, and the winding of device I² to terminal o. 45

A westbound train, when passing signal S³, will cause relay T² to become deenergized. Relay T², upon becoming deenergized, will open, at its contact 21, the circuit traced for relay H³. Relay H³, 50 upon becoming deenergized, will open, at the front point of its contact 5, the circuit for green lamp G of signal S³, and will again complete, at the back point of its contact 5, the circuit for red lamp R of signal S³. Relay H³ will also open, at the front 55 point of its contact 53, the circuit for indication device I², and will again complete, at the back point of its contact 53, the circuit traced for indication device J. Relay T², upon becoming deenergized, will also open, at its contact 13, the 60 stick circuit traced for relay U³, which will thereupon become deenergized.

The westbound train, upon entering section A—B, will cause relay T¹ to become deenergized, and this relay will then complete, at its contact 65 8, a pickup circuit for relay M², passing from terminal b, through contact 6 of relay H², contact 6 of relay H³, contact 8 of relay T¹, contact 9^b of relay T², and the winding of relay M² to terminal o. Relay M², upon becoming energized, will 70 again complete its stick circuit previously traced.

I will next assume that, with all parts of the apparatus again in their normal condition, the dispatcher again clears signal S³ for a westbound train to move from track Z to stretch X. I will 75

further assume that the dispatcher then decides to hold the westbound train at signal S³ until an eastbound train has proceeded from stretch X to track Y. He will therefore move lever V to its f position. This will cause transmitter K to supply receiver L with current of a code for opening contacts 12 and 40 for a brief period and for then closing contact 11 of receiver L. The opening of contact 12 of receiver L will break the stick circuit for relay U³, causing this relay to become deenergized.

Relay U³, upon becoming deenergized, will open, at its contact 34, the circuit previously traced for relay H³ which will therefore also become deenergized. Relay H³, upon becoming deenergized, will again open, at the front point of its contact 5, the circuit for green lamp G of signal S³, and will complete, at the back point of its contact 5, the circuit for the red lamp R of signal S³. Relay H³ will open, at the front point of its contact 53, the circuit for indication device I², and will again complete, at the back point of its contact 53, the circuit for indication device J.

Relay H³ will also complete a circuit for energizing relay E, passing from terminal b, through contact 6 of relay H², contact 6 of relay H³, back point of contact 7 of relay M², back point of contact 45 of relay M², contact 46 of relay T², and winding of relay E to terminal o. Upon the lapse of a measured period of time after the completion of this circuit, contact 10^a and 10^b of relay E will close.

The closing of contact 10^b will complete a pickup circuit for energizing relay M², passing from terminal b, through contact 6 of relay H², contact 6 of relay H³ contact 10^b of relay E, and the winding of relay M² to terminal o. Relay M², upon becoming energized, will again complete its stick circuit previously traced. The energization of relay M² will open, at the back points of contact 7 and 45, of this relay, the circuit traced for energizing relay E which, thereupon becoming deenergized, will open its contacts 10^a and 10^b and again close its contact 27.

The closing of contact 11 of receiver L caused relay U¹ to become energized as previously described.

With relay M² energized and with relay U¹ energized, the normal energizing circuit for relay W, previously traced, will now be completed. With relay W energized in the normal direction, a normal operating circuit for motor Q will be completed, passing from terminal b, through contact 47 of relay W, contact 50 of relay W in its left-hand position, armature 49 of motor Q, contact 48 of relay W in its left-hand position contact 51 of motor Q, and field winding 52 of motor Q to terminal o. Motor Q will then move dog a to its locking position. Upon the completion of the operation of dog a to its position for locking bar d, the circuit for energizing relay H¹, previously traced, will be completed at contact 33 of dog a, and hence signal S¹ will be cleared, as previously described, for the eastbound train.

I will now assume that all parts of the apparatus are again returned to their normal condition, and that the dispatcher desires to permit a train to move from track Y to stretch X. He will therefore move lever V to its f position, and will close push button contact P. The operation of lever V to its f position, closing contact 57, will cause transmitter K to supply receiver L with current of a code for closing contact 16 and thereby energizing relay U³ by its pickup circuit previously traced. The closing of push button con-

tact P while lever V is in its f position will cause transmitter K to supply receiver L with current of a code for closing contact 39 of receiver L. Contact 39 of receiver L, upon becoming closed, will complete a pickup circuit for relay U², passing from terminal b, through contact 39, and the winding of relay U² to terminal o. Relay U², upon becoming energized, will complete its own stick circuit passing from terminal b, through contact 40 of receiver L, contact 41 of relay U³, contact 42 of relay U², and the winding of relay U² to terminal o. The energization of relay U³ causes relay W to be energized in the reverse direction, which results in the operation of motor Q to move dog a out of engagement with bar d as previously described.

With dog a out of engagement with bar d, and with relay U² energized, a circuit will be completed for energizing relay H², passing from terminal b, through contact 20 of switch F, contact 21 of relay T², wire 22^b, contact 27 of relay E, wire 28^b, contact 34 of relay U³, contact 35 of relay H¹, contact 36 of relay T¹, contact 37 of dog a, contact 43 of relay U², and the winding of relay H² to terminal o. Relay H², upon becoming energized, opens, at its back contact 6, the stick circuit previously traced for relay M², causing relay M² to become deenergized. Relay H², upon becoming energized, also opens, at the back point of its contact 5, the circuit for red lamp R of signal S², and completes, at the front point of its contact 5, the circuit for lighting green lamp G of signal S². The energization of relay H² also opens, at the back point of its contact 54, the circuit previously traced for indication device J, and completes, at the front point of its contact 54, a second circuit for energizing indication device I², passing from terminal b, through the back point of contact 53 of relay H³, front point of contact 54 of relay H², and the winding of device I² to terminal o.

If for some reason an emergency operation of dog a is to be made by hand crank N, a trainman will insert crank N in the position in which it is shown in dash lines in the drawings, and will then operate crank N to disengage dog a from bar d. The placing of crank N in the position shown in dash lines opens contact 19, thereby breaking any pickup or stick circuit which may be closed for relay U³ or U¹. With both relays U¹ and U³ deenergized, relay W will be deenergized, and hence both the normal and the reverse operating circuits for motor Q will be open at contact 47 of relay W and cannot again be closed until crank N is removed to permit contact 19 to again close. After contact 19 becomes closed, no further energization of relay U¹ or U³ can take place for causing an operation of motor Q until the dispatcher again operates lever V for transmitting coded current for controlling receiver L.

From the foregoing description and the accompanying drawings, it follows that one form of apparatus embodying my invention comprises a track switch which is biased to a normal position and which may be of the well known spring switch type; and contacts selectively controlled by current of given codes for controlling a locking mechanism for locking or unlocking the switch and for causing a signal to be cleared for governing traffic movements in one direction or another over the switch while the switch is locked or unlocked, respectively.

I have described, for a few typical traffic movements, the operation of one form of apparatus embodying my invention. From this description

and from the accompanying drawings, the operation of the apparatus for every other possible traffic movement may be readily determined.

Although I have herein shown and described 5 only one form of remote control apparatus embodying my invention, it is understood that various changes and modifications may be made therein within the scope of the appended claims without departing from the spirit and scope of 10 my invention.

Having thus described my invention, what I claim is:

1. In combination, a railway track switch, a signal for governing traffic movements from a 15 given direction over said switch, a second signal for governing traffic movements from an opposite direction over said switch, a control relay, a second control relay, means for at times energizing said first control relay and for at other times 20 energizing said second control relay, a polarized switch relay, a circuit including a front contact of said first control relay for energizing said polarized relay by current of a given polarity, a second circuit including a front contact of said 25 second control relay for energizing said polarized relay by current of the opposite polarity, means controlled by said polarized relay for locking or unlocking said switch according as said polarized relay is energized by current of the one polarity 30 or the other, means controlled by said first control relay for clearing said first signal if said switch is locked, and means controlled by said second control relay for clearing said second signal if said switch is unlocked.

35 2. In combination, a stretch of railway track

including a switch, a track circuit including the rails of said stretch and provided with a track relay, a polarized relay, a circuit including a front contact of said track relay for energizing said polarized relay in the normal direction, a circuit for energizing said polarized relay in the reverse direction independently of the condition of said track relay, and means controlled by said polarized relay for locking or unlocking said switch according as said polarized relay is energized in the normal or the reverse direction.

3. In combination, a railway track switch, a first and a second normally open contact, manually controllable means for selectively closing said contacts, normally closed contact means opened by said manually controllable means when closing either of said normally open contacts, a first and a second stick relay, a pick-up circuit for said first stick relay and a pick-up circuit for said second stick relay controlled by said first and second normally open contacts respectively, a stick circuit for said first stick relay controlled by said normally closed contact means, a stick circuit for said second stick relay controlled by said normally closed contact means and by a front contact of said first stick relay, a first and a second signal for governing traffic movements over said switch, and means controlled by said stick relays for clearing said first signal when and only when said first stick relay is energized while 30 said second stick relay is deenergized and for clearing said second signal when and only when both said stick relays are energized.

PAUL P. STOKER. 35
